COMBINATION MISTER AND WATERING CAN

Jack Solomon, Island Park, N.Y., assignor to Pearl-Wick Corporation, Long Island City, N.Y.

Filed July 25, 1974, Ser. No. 491,936

Term of patent 14 years

Int. Cl. D23—01

U.S. Cl. D23—11

FIG. 1.

FIG. 2.

FIG. 3.

FIG. 4. FIG. 5.

FIG. 6.

FIG. 1 is a front elevational view of a combination mister and watering can showing my new design;

FIG. 2 is a top plan view thereof;

FIG. 3 is a bottom plan view thereof;

FIG. 4 is a left side view thereof;

FIG. 5 is a right side view thereof; and

FIG. 6 is a rear elevational view thereof.

I claim:

The ornamental design for a combination mister and watering can, substantially as shown.
